UNITED STATES PATENT OFFICE

168,617

VAPORIZER FOR HEATING AN INSECTICIDE

Arne B. Johnson, Madison, Wis.

Application January 30, 1952, Serial No. 18,304

Term of patent 3½ years

(Cl. D31—3)

To all whom it may concern:

Be it known that I, Arne B. Johnson, a citizen of the United States, residing in the city of Madison, county of Dane, State of Wisconsin, have invented a new, original, and ornamental Design for a Vaporizer for Heating an Insecticide, of which the following is a specification, reference being had to the accompanying drawing, forming a part thereof, in which:

Fig. 1 is a perspective view of a vaporizer for heating an insecticide showing my new design;

Fig. 2 is an elevational view thereof; and

Fig. 3 is a top plan view thereof.

I claim:

The ornamental design for a vaporizer for heating an insecticide, substantially as shown.

ARNE B. JOHNSON.
